DIOLEFIN PRODUCTION

José A. Samaniego, San Francisco, and Mott Souders, Jr., Piedmont, Calif., assignors to Shell Development Company, San Francisco, Calif., a corporation of Delaware

Application October 10, 1944, Serial No. 558,092

4 Claims. (Cl. 260—681.5)

1

This invention relates to an improved process for the separation of diolefins from hydrocarbon mixtures containing them and relates more particularly to an improved process for the more efficient production of substantially pure diolefins from hydrocarbon mixtures containing these diolefins in admixture with saturated and/or unsaturated hydrocarbons of similar boiling range. A specific embodiment of the invention relates to an improved process for the separation of substantially pure isoprene and piperylene from hydrocarbon fractions containing them.

The diolefins are finding ever increasing application as starting and intermediate materials in the production of a great number of products such as elastomers, resins, textiles, lacquers, dye-stuffs and related industries. Utilization of the diolefins in many of these industries has been handicapped by the inability to effect the complete and efficient separation, on a practical scale, of these hydrocarbons from other hydrocarbons of similar boiling range in admixture with which they are generally encountered. A principal source of the diolefins resides in the hydrocarbon mixtures produced by the pyrogenic or catalytic treatment of hydrocarbons or hydrocarbon mixtures of greater saturation than the diolefins. The resulting diolefin-containing hydrocarbon products, as is well known, consist of highly complex mixtures from which the separation of individual components such as, for example, a desired diolefin, by such methods as distillation, solvent extraction, etc., is often highly impractical if not impossible. Resort to separation by heretofore available means involving chemical reactions has often been exceedingly impractical due to the complexity of the operative steps involved and often because of the difficulties encountered in effecting the separation of diolefins from other unsaturated hydrocarbon by such means.

An advantageous method heretofore disclosed for the separation of diolefins from admixed hydrocarbons of similar boiling range makes use of the formation of the sulfone of the diolefin. Thus, it has been previously known that diolefins such as, for example, butadiene, isoprene, piperylene, etc., react with sulfur dioxide to form sulfones and that the diolefins are liberated when the sulfone is heated. Production of the diolefins in the high degree of purity essential to their efficient utilization in a great many processes is, however, seriously handicapped and often rendered impossible by the difficulties involved in effecting a practical recovery of a diolefin free of any substantial amount of other hydrocarbons

2

by such methods as disclosed heretofore. These difficulties inherent in these processes are attributable to the fact that the diolefin sulfone decomposes at a relatively low temperature, thereby rendering exceedingly difficult the separation, on a practical scale with a minimum of operative steps, of the hydrocarbons other than the desired diolefin generally unavoidably admixed therewith. Further difficulties inherent in these processes lie in the loss of diolefin due to the formation of polysulfones and in the ease with which the diolefin and the sulfur dioxide recombine under conditions which must be resorted to to effect their separation to any substantial degree by such means as fractionation.

It is an object of the present invention to provide an improved process for the more efficient separation of diolefins from hydrocarbon mixtures containing them.

Another object of the invention is the provision of an improved process for the more efficient separation of diolefins from hydrocarbon fractions of relatively narrow boiling range.

A more particular object of the invention is the provision of an improved process for the more efficient separation of piperylene and isoprene from hydrocarbon mixtures comprising these diolefins in admixture with other hydrocarbons of similar boiling range.

Another object of the invention is the provision of an improved process for the more efficient production of isoprene and/or piperylene, free of any substantial amount of other hydrocarbons, from hydrocarbon fractions predominating in hydrocarbons having five carbon atoms to the molecule.

In accordance with the present invention, a hydrocarbon mixture containing at least one diolefin such as, for example, a diolefin-containing hydrocarbon fraction obtained by the pyrogenic or catalytic treatment of aliphatic hydrocarbons, is contacted with sulfur dioxide in a reaction zone under conditions effecting the interaction of the sulfur dioxide and diolefins with the formation of the corresponding diolefin sulfones. Unreacted hydrocarbons and sulfur dioxide are separated from the sulfones in a two-stage operation comprising an initial flash vaporization of a substantial amount of unreacted hydrocarbons and sulfur dioxide from the sulfone in a vaporizing zone and the subsequent removal of substantially all remaining unreacted hydrocarbons from the sulfone by means of stripping with sulfur dioxide, obtained within the system, in a sulfone stripping zone maintained under conditions avoiding the

decomposition of the sulfones as well as the formation of polysulfones. The sulfone, now free of any substantial amount of unreacted hydrocarbons, is decomposed in a sulfone decomposing zone under conditions resulting in the formation of substantially only diolefin and sulfur dioxide. Effluence from the sulfone decomposing zone is contacted with a selective solvent for the diolefin in a diolefin extraction zone to effect the separation of the diolefin from the sulfur dioxide under conditions eliminating the difficulties arising from the facility with which sulfur dioxide and the diolefins recombine. The resulting diolefins, free of any substantial amount of sulfur dioxide and hydrocarbons other than the desired diolefins, are separated from the system as the final products. The relatively pure sulfur dioxide, eliminated from the extraction zone, is passed to the sulfone stripping zone to be used therein as the stripping medium. Vapors, comprising unreacted hydrocarbons and sulfur dioxide, from the vaporizing and sulfone stripping zones are treated to effect the removal of at least a substantial amount of the unreacted hydrocarbons therefrom and are then recycled to the reaction zone.

In order to set forth more fully the nature of the invention it will be described in detail herein in its application to the production of isoprene and piperylene from hydrocarbon mixtures containing these diolefins, with reference to the attached drawing forming a part of the present specification and wherein the single figure illustrates one form of apparatus suitable for executing the process of the invention.

A suitable charge material for the process of the invention is a diolefin-containing hydrocarbon fraction such as, for example, a hydrocarbon fraction consisting predominantly of unsaturated hydrocarbons having five carbon atoms to the molecule, as obtained in the fractionation of the distillate products of the high temperature cracking in the vapor phase of naturally occurring hydrocarbon mixtures or fractions thereof. The charge is preferably fractionated to obtain an acyclic diolefin concentrate containing substantially all of the isoprene and piperylene. The acyclic diolefin concentrate is preferably freed of any substantial moisture content, for example, by passage through any suitable drying agent. The resulting dry acyclic diolefin-containing hydrocarbon mixture is passed through line 10 into a suitable reaction zone. The reaction zone may comprise a reactor of enlarged cross sectional area 11. Although but one such reactor is shown in the drawing, a plurality of such reactors connected in series or in parallel may suitably be used. Sulfur dioxide, recycled from within the system through line 12 as described more fully herein below, is introduced into line 10 to mix with the hydrocarbon charge flowing therethrough. The amount of sulfur dioxide thus introduced into line 10 may vary considerably within the scope of the invention. It is, however, preferred to introduce the sulfur dioxide at a rate enabling the maintenance of a substantial molar excess of sulfur dioxide over diolefins in reactor 11.

Conditions of temperature and pressure maintained within reactor 11 may vary considerably within the scope of the invention. Conditions are, however, preferably carefully controlled to effect the reaction of sulfur dioxide with isoprene and piperylene with the formation of isoprene sulfone and piperylene sulfone as the predominant reaction. Particularly advantageous

results are obtained with the use of a temperature of about 100° C., though somewhat higher or lower temperatures may be employed. It is to be stressed that the sulfones are ordinarily decomposed at relatively low temperatures and that therefore temperatures within the reactor are preferably controlled to remain below the temperature at which any substantial decomposition of sulfones is encountered. Maintenance of a substantial excess of sulfur dioxide in the reaction zone enables the utilization of higher reaction temperatures than would be possible in the absence of such excess of sulfur dioxide. Pressures within reactor 11 are preferably sufficiently high to maintain at least a substantial part of the reactants in the liquid phase. As a general rule the pressure within reactor 11 is preferably maintained in excess of about 150 pounds per square inch and still more preferably in excess of about 350 pounds per square inch. Temperature conditions within reactor 11 are controlled by the passage of vaporized reactants from reactor 11 into suitable cooling means, for example, a condenser 14, wherein latent heat of vaporization is withdrawn from the vapors, and return of the resulting condensate to the reactor. Under the above-defined reaction conditions isoprene and piperylene in the hydrocarbon charge react with sulfur dioxide to form isoprene sulfone and piperylene sulfone respectively in the absence of any substantial side reactions such as, for example, olefin sulfonation.

As pointed out above, it is essential to the attainment of a product of the desired purity that substantially all of the unreacted hydrocarbons other than isoprene and piperylene in admixture with the sulfones be separated therefrom. Subjecting the reaction products to such means as simple fractionation to effect such complete separation requires the need of substantial additional heat input into the reaction products at a temperature level exceeding by far the maximum reactor temperature generally employed. Since the sulfones are decomposed at relatively low temperatures, such treatment, resulting in a reversal of the sulfone producing reaction in the fractionating zone, would render the system highly impractical. Thus, isoprene sulfone, for example, undergoes decomposition at a temperature substantially below its boiling temperature. These difficulties are overcome in the process of the invention by the utilization of a two-step separation wherein unreacted hydrocarbons are separated from the sulfones at temperatures which are generally lower than the reaction temperature, thereby obviating any tendency towards sulfone decomposition. The method of separation inherent in the process of the invention not only avoids the decomposition of sulfones but enables substantially complete separation of unreacted hydrocarbons from the diolefin sulfones produced.

To effect the separation of the unreacted hydrocarbons from the sulfones, effluence from reactor 11 is passed through valved line 16 into a vaporizing zone comprising, for example, enlarged chamber 17. By a suitable reduction of pressure and controlled heat input by means of closed coil 18, a substantial part of the unreacted hydrocarbons and sulfur dioxide are separated from the diolefin sulfones in vaporizer 17. The diolefin sulfones and remaining sulfur dioxide and unreacted hydrocarbons, are forced through line 19 into a stripping zone comprising, for example, a stripping column 20. Within stripping

column 20 the sulfones are stripped with sulfur dioxide introduced into the lower part of the column by means of line 22, thereby effecting the removal of substantially all of the remaining unreacted hydrocarbons from the diolefin sulfones. Temperatures within vaporizing chamber 17 and stripping column 20 are maintained substantially at and preferably below the temperature maintained in the reactor 11. Thus, the temperature in vaporizer 17 and stripping column 20 is preferably maintained below about 100° C. Maintenance of a temperature of about 90° C. and a pressure of about 100 pounds per square inch in vaporizer 17 and stripping column 20 is found to be highly advantageous. Any heat input into stripping column 20, required to aid in effecting the desired separation, is accomplished by the passage of bottoms from the column through a heater 23 and thence back into the column. Since it is essential that any substantial increase in temperature of the diolefin sulfones be avoided, heater 23 is of a type enabling the rapid passage of liquid therethrough to result in but a moderate increase in temperature. It is found that a temperature gradient substantially in excess of about 5° C. from inlet to outlet of heater 23 is generally not needed and is therefore to be avoided. Under the above defined two-stage separation the hydrocarbon content of the sulfones taken from the lower part of stripper 20 is readily maintained at an unusually low level, for example, at about 0.1 mol per cent and less.

Vapors eliminated from vaporizer 17 comprising sulfur dioxide and unreacted hydrocarbons are passed through line 26 to a fractionator 27. Sulfur dioxide containing unreacted hydrocarbons, eliminated overhead from stripping column 20, is passed through line 28 into line 26. Within fractionator 27 there is separated a vapor fraction comprising sulfur dioxide and a minor amount of unreacted hydrocarbons from a liquid fraction comprising unreacted hydrocarbons. The liquid fraction is eliminated from the system through valved line 28. Due to the tendency of isopentane and pentane to form azeotropes with sulfur dioxide, the vapor overhead of column 27 will comprise a mixture generally consisting of sulfur dioxide containing from about 12% to about 15% of pentanes.

The vapor overhead from column 27 is passed through line 30 and condenser 31 into a receiver 33. Liquid comprising sulfur dioxide and a minor amount of saturated hydrocarbons is taken from receiver 33 and forced through line 12 into line 10 leading to the reaction zone. If desired, the hydrocarbon content of the sulfur dioxide stream passing through line 12 may be reduced. By suitable adjustment of valves 34, 35 and 36 at least a part of the stream may be diverted from line 12, through cooler 37, into a separator 38. In passing through cooler 37 the stream is cooled to a temperature sufficiently low to effect the separation within cooler 38 of a supernatant hydrocarbon layer from a lower layer consisting of sulfur dioxide having a lower hydrocarbon content than the liquid in accumulator 33. Cooling the stream flowing through cooler 37 to a temperature of about -10° C. results in reduction of the hydrocarbon content of the lower layer in separator 40 to about 7% by weight. The lower layer is passed through valved line 39 into line 12. The supernatant hydrocarbon layer containing a minor amount of sulfur dioxide is taken from separator 38 and passed through line 40 to fractionator 27. In this wise the hy-

drocarbons eliminated from the recycling sulfur dioxide stream are ultimately eliminated from the system through valved line 28. A valved line 41 is provided for the introduction of make-up sulfur dioxide into the system.

Liquid consisting of isoprene sulfone and piperylene sulfone is continuously passed from heater 23 through line 45 into a sulfone decomposing zone. The sulfone decomposing zone may suitably comprise an enlarged chamber 46 provided with suitable heating means such as, for example, closed heating coil 47. Within decomposer 46 the sulfones are raised to a temperature sufficiently high to effect their decomposition resulting in the liberation of the diolefins. Maintenance of temperatures in excess of about 125° C. and preferably in the range of, for example, from about 130° C. to about 175° C. and a pressure, for example, in the range of from about 15 pounds to about 300 pounds and preferably in the range of from about 100 pounds to about 150 pounds per square inch within the decomposer 46 have been found advantageous. Under the above defined conditions isoprene sulfone is decomposed to isoprene and sulfur dioxide, and piperylene sulfone is decomposed to piperylene and sulfur dioxide. In order to avoid the formation of undesired reaction products, for example, materials comprising polysulfones, unnecessarily high temperatures and a residence time longer than that essential to the obtaining of the desired dienes are avoided in decomposer 46. From chamber 46 decomposition products consisting of the dienes and sulfur dioxide are passed through line 50 into an extraction column 51. Within extraction column 51 the products are contacted countercurrently with a selective solvent for the dienes such as, for example, a paraffinic hydrocarbon, preferably one having at least seven carbon atoms to the molecule. A suitable solvent comprises octanes. Although paraffinic hydrocarbons have been chosen as preferred solvents for selective removal of the dienes from the sulfur dioxide admixed therewith, the invention is in no wise limited to the utilization of any specific solvent and any solvent capable of effecting the selective removal of the dienes may be used. Thus, such suitable selective solvents for the dienes comprise, for example, the hydrocarbons having a greater degree of saturation than the dienes extracted therewith or a mixture predominating in one or more such hydrocarbons, etc.

Rich solvent containing isoprene and piperylene is passed from the lower part of extraction column 51 into a soaking zone. The soaking zone consists of an enlarged chamber 53 provided with suitable heating means such as, for example, a coil 54. Within soaker 53 the rich solvent containing the diolefins is maintained for a period of time at a sufficiently high temperature to assure the decomposition of any diolefin sulfones which may have formed during the extractive operation and also to prevent the further combination of any small amounts of sulfur dioxide still present with the diolefin product. Vapors from soaker 53 consisting of diolefins, octanes and any sulfur dioxide which may have entered into soaker 53 are returned to column 51 through valved line 55. Temperatures within the soaker may advantageously be maintained in the range of, for example, from about 120° C. to about 175° C. At times it may be desirable to maintain a temperature within soaker 53 in excess of that maintained in the bottom of

column 51. To this intent, line 52 is provided with a pump 57 and line 55 with a valve 58 to enable the maintenance of higher pressures within soaker 53 than those maintained within column 51.

Liquid comprising solvent, isoprene and piperylene is passed from soaker 53 through valved line 60 into a still 61. Within still 61 there is separated a vapor fraction comprising the isoprene and piperylene from a liquid fraction comprising the solvent. The solvent is returned to column 51 by means of line 62. A cooler 63 is provided in line 62 to effect the desired cooling of the solvent prior to introduction into column 51. A valved line 64 is provided for the introduction of make-up solvent into line 62. The vapor fraction is passed overhead from column 61 through line 65 and condenser 66 into an accumulator 67. From accumulator 67 liquid comprising isoprene and piperylene is passed to a neutralizing zone by means of line 68. The neutralizing zone may comprise a contacting chamber 69 wherein the hydrocarbon stream is contacted with a suitable neutralizing agent such as, for example, an aqueous sodium hydroxide solution or the like, and a settling chamber 70 wherein separation of treating agent from hydrocarbons is effected. It is to be understood that the invention is in no wise limited by the type of neutralizing system employed and any conventional method for removing traces of remaining sulfur dioxide from the diolefin product may be resorted to. From separator 70 the diolefins are passed through line 71 into a fractionating column 72. Within fractionator 72 there is separated a vapor fraction consisting essentially of isoprene from a liquid fraction consisting essentially of piperylene. Liquid comprising piperylene is withdrawn from the lower part of column 72 by means of valved line 73. Vapors comprising isoprene are taken overhead from column 72 and passed through line 74, condenser 75, into accumulator 76. Liquid comprising isoprene is withdrawn as a final product from accumulator 76 through valved line 77.

The sulfur dioxide separated from the sulfone decomposition products in extraction column 51 is passed overhead therefrom through line 22 into the lower part of column 20 to function as the stripping agent therein. A valved line 78 is provided for the introduction of additional sulfur dioxide into line 22, should this be required. It is to be pointed out that a highly important feature of the invention, contributing materially to the increased efficiency with which diolefins can be separated from hydrocarbons admixed therewith, resides in the utilization of sulfur dioxide emanating only from the sulfone decomposing zone as the stripping agent in the sulfone stripping zone, and the recycling to the reaction zone wherein the sulfones are formed, of sulfur dioxide emanating only from the vaporizing and sulfone stripping zones.

Since impurities in the charge, particularly oxygen and organic peroxides are detrimental to efficient execution of the process, the hydrocarbon feed is preferably subjected to any suitable pretreatment which may comprise such steps as, for example, distillation over caustic followed by passage through suitable drying agents.

The detailed illustrative description of the invention has been directed to the separation of both isoprene and piperylene from a hydrocarbon mixture containing them. It is to be stressed, however, that by suitable control of conditions

in reactor 11 but one of the diolefins may be separated from the feed to the process. Thus, by limiting the time of contact in reactor 11 the sulfone reaction product can be made to consist predominantly of isoprene sulfone even though piperylene is present in the charge. The process of the invention is furthermore not limited to the separation of only diolefins having five carbon atoms to the molecule but is applicable broadly to the

separation of other diolefins such as, for example, 2-methyl-1,3-pentadiene, from hydrocarbon mixtures containing them.

The following example consisting of one specific continuous operation is given as illustrative of the method of separating diolefins from admixture with hydrocarbons of similar boiling range in accordance with the process of the invention.

Example

An unsaturated hydrocarbon fraction, obtained by fractionation of the distillate products of the vapor phase cracking of gas oil, consisting predominantly of unsaturated hydrocarbons having five carbon atoms to the molecule is distilled over caustic, dried, and again fractionated to separate therefrom a C₅ diolefin concentrate having the following composition:

	Mol per cent
C ₅ paraffins	3.3
C ₅ olefins	31.9
Isoprene	40.3
Piperylene	24.5

The diolefin concentrate is mixed with SO₂ in a molar ratio of SO₂ to total dienes of 5:1 and is passed into the sulfone reactor maintained at a temperature of 99° C. and a pressure of 400 pounds per square inch. Reactor effluence having a composition of:

	Mol per cent
C ₅ paraffins	12.9
C ₅ olefins	7.6
Isoprene	0.5
Piperylene	1.5
SO ₂	63.9
Sulfones	13.6

is passed into the vaporizer maintained at 80° C. and 100 pounds per square inch wherein SO₂ and hydrocarbons are flashed off. The sulfone residue is passed into the sulfone stripper wherein it is stripped with SO₂, obtained within the system, at a temperature of 80° C. and a pressure of 100° C. The resulting stripped mixture of isoprene sulfone and piperylene sulfone containing 54 mol per cent SO₂ and only 0.46 mol per cent of C₅ hydrocarbons (including unreacted diolefins) is introduced into the sulfone decomposer wherein it is subjected to a temperature of 149° C. and a pressure of 125 pounds per square inch. Effluence from the sulfone decomposer having the following composition:

	Mol per cent
SO ₂	68.1
Isoprene	21.3
Piperylene	10.5
High boiling material	0.1

is passed into the diene extraction column wherein it is contacted with a countercurrent flow of hot acid octanes. Rich octane solvent containing absorbed isoprene and piperylene is passed from the absorber to the soaker maintained at a temperature of 142° C. SO₂ eliminated overhead from the extraction column is passed to the sul-

fone stripper. SO_2 eliminated from the vaporizer and the sulfone stripper are combined and the resulting mixture, containing 22.6 mol per cent of C_5 hydrocarbons, is passed into the SO_2 fractionator wherein an overhead product consisting of SO_2 containing 13.5 mol per cent C_5 hydrocarbons is separated and recycled to the reactor. Liquid is drawn from the soaker and distilled to separate isoprene and piperylene. The resulting dienes are caustic treated and fractionated to separate piperylene of a purity of 90% from isoprene of a purity of 99%. The isoprene and piperylene thus obtained constitute 85% and 72% respectively of the isoprene and piperylene charged to the system.

We claim as our invention:

1. In a process for recovering isoprene and piperylene from a hydrocarbon mixture containing isoprene and piperylene in admixture with other hydrocarbons of a greater degree of saturation than said isoprene and piperylene wherein in said hydrocarbon mixture is contacted with sulfur dioxide in a reaction zone under conditions resulting in the formation of reaction products predominating in diolefin sulfones consisting essentially of isoprene sulfone and piperylene sulfone in admixture with sulfur dioxide and unreacted hydrocarbons and said reaction products are heated in a decomposition zone at a temperature sufficiently high to decompose diolefin sulfones with the liberation of isoprene and piperylene, the steps which comprise passing reaction products from the reaction zone into a vaporizing zone, separating a vapor fraction comprising sulfur dioxide and unreacted hydrocarbons from a liquid fraction comprising diolefin sulfones, sulfur dioxide and residual unreacted hydrocarbons in said vaporizing zone, stripping said liquid fraction with sulfur dioxide in a stripping zone, thereby removing substantially all residual unreacted hydrocarbons from said diolefin sulfones in the absence of side reactions to any substantial degree, and passing diolefin sulfones free of any substantial amount of unreacted hydrocarbons from the stripping zone to the decomposition zone, contacting the effluence from said decomposition zone comprising isoprene, piperylene and sulfur dioxide with a countercurrent stream of a selective solvent for said diolefins in an extraction zone, thereby selectively absorbing isoprene and piperylene in said solvent, separating isoprene and piperylene from the resulting rich solvent containing isoprene and piperylene, and passing sulfur dioxide from said extraction zone to said stripping zone.

2. In a process for recovering an acyclic diolefin from a hydrocarbon mixture containing said acyclic diolefin in admixture with other hydrocarbons of a greater degree of saturation than said diolefin wherein said hydrocarbon mixture is contacted with sulfur dioxide in a reaction zone under conditions resulting in the formation of reaction products predominating in the sulfone of said acyclic diolefin in admixture with sulfur dioxide and unreacted hydrocarbons and said reaction products are heated in a decomposition zone at a temperature sufficiently high to decompose said diolefin sulfone with the liberation of said diolefin, the steps which comprise passing reaction products from the reaction zone into a vaporizing zone, separating a vapor fraction comprising sulfur dioxide and unreacted hydrocarbons from a liquid fraction comprising diolefin sulfone, sulfur dioxide and residual unreacted hydrocarbons in said vaporizing zone, stripping said

liquid fraction with sulfur dioxide in a stripping zone, thereby removing substantially all residual unreacted hydrocarbons from said diolefin sulfone in the absence of side reactions to any substantial degree, and passing diolefin sulfone free of any substantial amount of unreacted hydrocarbons from the stripping zone to the decomposition zone, contacting the effluence from the decomposition zone comprising diolefin and sulfur dioxide with a countercurrent stream of selective solvent for said diolefin, thereby selectively absorbing said diolefin in the solvent, separating said diolefin from the resulting rich solvent containing said diolefin, and passing sulfur dioxide from the extraction zone to the stripping zone.

16 ~~1. RECOVERING ISOPRENE FROM A HYDROCARBON MIXTURE~~ to the stripping zone.

3. In a process for recovering isoprene from a hydrocarbon mixture comprising isoprene in admixture with hydrocarbons of a greater degree of saturation wherein said hydrocarbon mixture is contacted with sulfur dioxide in a reaction zone under conditions resulting in the formation of reaction products predominating in diolefin sulfones consisting essentially of isoprene sulfone in admixture with sulfur dioxide and unreacted hydrocarbons and said reaction products are heated in a decomposition zone at a temperature sufficiently high to decompose said diolefin sulfones with the liberation of isoprene, the steps which comprise passing reaction products from the reaction zone into a vaporizing zone, separating a vapor fraction comprising sulfur dioxide and unreacted hydrocarbons from a liquid fraction comprising diolefin sulfones, sulfur dioxide and residual unreacted hydrocarbons in said vaporizing zone, stripping said liquid fraction with sulfur dioxide in a stripping zone to remove substantially all unreacted hydrocarbons therefrom in the absence of any undesirable side reactions to any substantial degree, passing diolefin sulfones free of any substantial amount of residual unreacted hydrocarbons from the stripping zone to the decomposition zone, contacting effluence from said decomposition zone comprising isoprene and sulfur dioxide with a selective solvent for said diolefins in an extraction zone, thereby selectively absorbing isoprene in said solvent, separating isoprene from the resulting rich solvent containing isoprene and passing sulfur dioxide from the extraction zone to the stripping zone.

50 4. In a process for recovering piperylene from
a hydrocarbon mixture comprising piperylene in
admixture with hydrocarbons of a greater degree
of saturation wherein said hydrocarbon mixture is
contacted with sulfur dioxide in a reaction zone
55 under conditions resulting in the formation of
reaction products predominating in diolefin sul-
fones consisting essentially of piperylene sulfone
in admixture with sulfur dioxide and unreacted
hydrocarbons and said reaction products are
heated in a decomposition zone at a temperature
60 sufficiently high to decompose said diolefin sul-
fones with the liberation of piperylene, the steps
which comprise passing reaction products from
the reaction zone into a vaporizing zone, sepa-
65 rating a vapor fraction comprising sulfur diox-
ide and unreacted hydrocarbons from a liquid
fraction comprising diolefin sulfones, sulfur diox-
ide and residual unreacted hydrocarbons in said
vaporizing zone, stripping said liquid fraction
70 with sulfur dioxide in a stripping zone to remove
substantially all unreacted hydrocarbons there-
from in the absence of any undesirable side re-
actions to any substantial degree, passing diole-
fin sulfones free of any substantial amount of
75 residual unreacted hydrocarbons from the strip-

11

ping zone to the decomposition zone, contacting effluence from said decomposition zone comprising piperylene and sulfur dioxide with a selective solvent for said diolefins in an extraction zone, thereby selectively absorbing piperylene in said solvent, separating piperylene from the resulting rich solvent containing piperylene and passing sulfur dioxide from the extraction zone to the stripping zone.
